UNITED STATES PATENT OFFICE.

ALONZO FRAZER, OF ST. LOUIS, MISSOURI.

SHOE.

1,134,189.

Specification of Letters Patent. Patented Apr. 6, 1915.

Application filed April 1, 1913. Serial No. 758,185.

To all whom it may concern:

Be it known that I, ALONZO FRAZER, a citizen of the United States of America, and a resident of the city of St. Louis and 5 State of Missouri, have invented certain new and useful Improvements in Shoes, of which the following is a full, clear, and exact description, reference being had to the accompanying drawings, forming a part of 10 this specification.

My invention relates to a lined shoe of the type known to the trade as "stitchdown" shoes, the uppers of which are turned outwardly in lasting.

15 Lined "stitchdown" shoes, as heretofore made, as far as I am aware, have included, besides outer members and linings of uppers, an outer sole and a separate inner sole.

One of the objects of my invention is to so 20 construct a lined "stitchdown" shoe as to eliminate the use of a separate inner sole, thereby lessening the expense of production, and rendering the shoe more flexible.

A further object of my invention is to join 25 the outer member and lining of the upper and the outer sole in such manner as to render the connection between these members stronger and more secure than in "stitchdown" shoes previously produced. This 30 object is obtained by forming a combined inner and outer sole with an upstanding abutment corresponding to the edge of an inner sole, and driving staples or the like through the upper and into the upstanding face of 35 said abutment at points above the base of said abutment, so as to firmly force the lining against the upstanding face of said abutment.

A still further object of my invention is 40 to produce a lined "stitchdown" shoe that may be supplied with a new sole as readily and perfectly as to other types of shoes, either by stitching, pegging, or nailing operations.

45 Figure I is a perspective view of the sole of a shoe made in accordance with my invention. Fig. II is an enlarged cross section including only a side portion of the shoe, and illustrating the fastening means 50 for securing the upper directly to the abutment at the edge of the sole. Fig. III is a view similar to Fig. II, illustrating a side portion of a shoe having a single section outer sole in lieu of the double section outer 55 sole shown in Fig. II.

Referring to the accompanying drawings: The outer sole of my shoe, as illustrated in Fig. II, comprises two sections A and C and, as illustrated in Fig. III, comprises a single section. I will, in the following description, refer more particularly to the double section sole, with the understanding, however, that my invention pertains also to a shoe in which the single section sole is present, and in the description, with reference to Fig. II, will designate the section A as the upper sole section, and the section C as the lower sole section of the shoe. The single section sole shown in Fig. III will be considered an outer sole designated A'. 60 65 70

The sole section A is cut inwardly relative to its edge and downwardly from its top face to form a channel 1, at the inner edge of which is a shoulder or lip 2, the channel serving to receive the outturned wings b and 75 d of the outer member B of the upper and the lining D, respectively. It should be here mentioned that the cutting of the sole section A to produce the channel 1 is preferably such as to avoid material lessening of 80 the thickness of the marginal portion of the sole section A at and near the edge of such section, so that the production of the channel does not objectionably weaken the portion of the sole section to which the out- 85 turned wings of the elements of the upper are secured. It should also be mentioned at this point in the description that the channel 1 is preferably so produced as to render the shoulder or lip 2 of undercut form and produce a feather edge 3 at the top of the shoulder or lip. 90 95

In the manufacture of my shoe, the sole section A is channeled and provided with a shoulder or lip extending throughout so much of the sole as it may be desired to channel for the reception of the upper in accordance with my invention; and the upper is produced with the outturned wings b and d, which fit in the channel 1, with the vertical portion of the lining of the upper resting against the shoulder or lip 2, the latter serving as an abutment. The outer member and lining of the upper are then first secured to the sole by suitable fastening means, such, for example, as staples 4, (see Figs. II and III), driven through the vertical portions of both the outer member and lining of the upper and into the abutment 2 to connect these parts, hold them in 100 105 110

firm engagement with each other, firmly force the lining against the abutment, and strengthen the shoes at the junction of the upwardly extending portion of the upper 5 and the sole. In thus connecting the upper to the sole section A, I provide for the presence of the central portion of said sole section within the shoe, and this portion, therefore, serves as an inner sole, integral 10 with the sole section A and directly connected to the upper. Furthermore, by this construction, the lining of the upper is confined and held to the abutment with the outer main member of the upper, so that 15 there is no opportunity for loosening of the lining as in the case where the upper is secured to the sole only at points below such abutment, and the feather edge 3 being firmly seated against the inner wall of the 20 lining, furnishes a curved face extending from the central portion of the sole section A upwardly and outwardly to the upper, such as is desirable to give a neat and desirable contour to the interior of the shoe 25 at the junction of the sole and the lining of the upper.

The margins of both the outer member and lining of the upper are fastened securely and firmly to the sole by stitching 5 30 that extends through these members and preferably, also, through a reinforcing and finish strip 6 overlying the marginal wing of the upper.

It will be seen that by constructing a lined 35 "stitchdown" shoe in accordance with my invention, there is absolutely no occasion for the use of a separate inner sole, and it will be appreciated that the inner sole portion of the sole section A, or sole A', constitutes in effect an inner sole which meets 40 all of the demands for such an element in a shoe.

It will be obvious that the connection between the upper and the outer sole of a 45 shoe of the kind described herein is much stronger and much more secure than it is in lined "stitchdown" shoes as heretofore

made, this being due to the presence of the shoulder or lip provided upon the sole, and the provision of fastening means whereby 50 the outer member and lining of the upper are attached to the sole at the location of such shoulder or lip.

While I have herein described my invention as pertaining to shoes, it will be obvious that boots and other articles of footwear may be constructed in accordance with my invention, and although the invention is claimed as an improvement in "stitchdown" shoes, I desire to be understood as 60 claiming my invention when made use of in any kind of "stitchdown" footwear.

I claim:—

In a shoe, an upper comprising an outer member and a lining, and a combined inner 65 and outer sole member consisting of a single piece of material having an undercut abutment provided with an upstanding face to which the lining is fitted, said undercut abutment corresponding in location to the 70 edge of an inner sole, and the said undercut abutment terminating in a free feather edge which engages said lining, both the outer member of the upper and the lining being turned outwardly at the base of said undercut abutment and sewed to said combined inner and outer sole member at points beyond the base of said undercut abutment; combined with members driven through substantially vertical portions of both the 80 lining and outer member of said upper and into the upstanding face of said undercut abutment at points above the base of said undercut abutment, so as to firmly force the lining against the upstanding face of said 85 abutment, thereby reinforcing the shoe at the junction of said upper and the combined inner and outer sole member, at the same time firmly forcing said lining against said free feather edge.

ALONZO FRAZER.

In the presence of—

M. FALVEY,
E. B. LINN.
